Geo. B. Willard ATTORNEY

UNITED STATES PATENT OFFICE.

HERMAN BESSER, OF ALPENA, MICHIGAN.

CONCRETE RAILROAD-TIE.

1,217,555.

Specification of Letters Patent. Patented Feb. 27, 1917.

Application filed October 9, 1914. Serial No. 865,825.

To all whom it may concern:

Be it known that I, HERMAN BESSER, a citizen of the United States, residing at Alpena, in the county of Alpena and State 5 of Michigan, have invented certain new and useful Improvements in Concrete Railroad-Ties; and I do hereby declare the following to be a full, clear, and exact description of the invention, such as will enable others 10 skilled in the art to which it appertains to make and use the same.

This invention is a concrete railway tie, and the invention pertains more particularly to an improved construction and arrangement 15 of the internal reinforcing of the concrete tie, in combination with a tie plate or rail cushion that cooperates with the internal reinforcing of the tie to prevent wear on the tie or crumbling of the concrete.

20 With these and certain other objects in view which will appear later in the specification, my invention consists in the devices described and claimed and the equivalents thereof.

25 In the drawings, Figure 1 is a part horizontal section of a tie embodying my improvement.

Fig. 2 is a part sectional side elevation.

Fig. 3 is a detail of one form of rail-30 fastening device.

Fig. 4 is a part sectional detail of a tie and rail with the rail-fastening illustrated in Fig. 3 in place.

Fig. 5 is a perspective view of one form 35 of rail cushion.

Fig. 6 is a part sectional perspective of a modified form of rail cushion and rail-fastening.

Fig. 7 is a perspective detail of the modified 40 form of cushion shown in Fig. 6.

Fig. 8 shows a modified form of rail-fastening plate that also serves as a rail brace.

Fig. 9 is a part vertical longitudinal section through the end of a tie showing a 45 modified arrangement for the nest of reinforcing material.

As is clearly shown in the drawings, the railway tie consists of two concrete tie members 1 and 2, which may be fastened together 50 along the center line of the railway track by means of tie bars 3 and bolts 4, or their equivalents.

55 In carrying out my invention, I reinforce the tie members 1 and 2 by embedding in them strips of expanded metal 5, the strips being set on edge and preferably extending

from the top surface of the tie member down to the bottom of the member, or nearly to the bottom. The strips 5 may be bent in any suitable manner, but I prefer the arrangement shown in Fig. 1, in which one of the strips 5 extends along one side of the tie member and part way across its end, and the opposite strip 6 similarly extends along the outer side of the tie member, so that the 60 two strips together partly inclose the body 65 of the tie near its outside.

The outer ends of the reinforcing may be folded back upon themselves as at 7 in Fig. 1, or if desired they may be bent so as to extend 70 across the end of the tie as at 8.

In that part of the tie that supports the rail flange, I prefer to embed a number of layers of expanded metal set on edge. These layers may be arranged as shown in Fig. 1 75 by bending a strip of expanded metal back and forth upon itself to form a nest 9 embedded in the body of the tie. They may also be arranged in any other suitable manner with the planes of the meshes vertical, as 80 for illustration, with the bends of the strips at the top and bottom as shown in Fig. 9.

The purpose of the reinforcing strips 5 and 6 and of the nest of strips 9 is to reinforce the concrete against crumbling and 85 disintegrating at the point where such action is most likely to occur on account of the vibration of the rails when trains pass over the tie.

I further strengthen and reinforce the end 90 of the tie by means of a rail-fastening and rail cushion or tie plate.

In the form shown in Figs. 3, 4 and 5, the tie plate or cushion consists in a flat plate 10 having downwardly extending flanges 11 95 engaging the sides of the tie member 1. The flanges 11 may be formed with slots 11^a if desired, to impart additional resilience to the tie plate 10.

Bolts 12 pass through the tie from side to 100 side to secure the flanges 11 in place. The bolts also serve to clamp the rail-fastening plates 13 to the flanges 11, the fastening plates being formed with openings 14 to receive the bolts 12.

The upper edge of each fastening plate 13 is provided with a hooked member 15 adapted to take over the edge of the rail flange 16 as shown in Figs. 1, 2 and 4. The fastening plate may be formed if desired with a hooked member, as shown in Fig. 8, adapted 110 to extend to and engage the web of the rail,

and serve as a rail brace. This construction is desirable for use on curves.

It will be noted that the bolts 12 and the flanged tie plate 10 assist in sustaining the nest 9 of reinforcing material and in reducing the liability of the concrete crumbling when subjected to repeated impacts.

In the modified form of cushion shown in Figs. 6 and 7 the plate is formed in two parts, each of which comprises a horizontal member 17 and a vertical flange 18, the flange being perforated to receive bolts 19 that pass through the tie from side to side. With this form of cushion plate the rail-fastening plates 13 shown in Fig. 4 may be used, or if desired, the rail flange 16 may be held in place by means of suitable clips 20 riveted or otherwise secured to the horizontal plate members 17 of the rail cushion, as shown in Fig. 6, where clip 20 is riveted to the horizontal member of one half of the two-part cushion and the opposite clip is riveted to the other half of the cushion, to enable the two halves of the cushion with their clips attached, to be readily assembled on the tie.

When the plate 10 and its flanges 11 are formed in one piece, as shown in Fig. 4, the bolts are inserted after the plate has been put in place, holes having been left in the tie to receive the bolts.

In the form of cushion shown in Fig. 6, the bolts may be embedded in the concrete tie with their ends projecting and the two-part plate 17 may be assembled on the tie after it has been molded with the bolts in place.

While I have described the reinforcing material as being made of expanded metal,

it is apparent that any equivalent of expanded metal, such as metal fabric of any suitable character, could be used without departing from the spirit of my invention.

By the means above described, I have produced a concrete tie which is strongly reinforced in that part which is directly subjected to the pounding action of the rail, the cushion and the rail-fastening device co-operating with the reinforcing to prevent crumbling of the tie.

Having thus described my invention, what I claim and desire to secure by Letters Patent is:

1. In a concrete railway tie, a reinforcing device comprising a strip of metal fabric folded repeatedly back and forth upon itself, with the layers arranged vertically and spaced apart and embedded in the concrete beneath the rail-supporting part of the tie.

2. In a concrete railway tie, a reinforcing device comprising strips of metal fabric embedded in the concrete beneath the rail-supporting part of the tie, said strips folded repeatedly back and forth upon themselves, with the layers arranged vertically and spaced apart, a rail-fastening and tie-clamping plate carried by said tie above said reinforcing strips, and bolts extending through the plate, tie and reinforcing strips, and means for tightening said bolts to clamp said plate to said tie, for the purposes set forth.

In testimony whereof, I affix my signature in presence of two witnesses.

HERMAN BESSER.
